ELECTRIC MIXER

Joseph R. Corbett, Cincinnati, Ohio

Application December 31, 1953, Serial No. 28,295

Term of patent 14 years

(Cl. D44—1)

To all whom it may concern:

Be it known that I, Joseph R. Corbett, a citizen of the United States, residing at Cincinnati, in the county of Hamilton and State of Ohio, have invented a new, original, and ornamental Design for an Electric Mixer, of which the following is a specification, reference being had to the accompanying drawings, forming a part thereof.

Figure 1 is a side elevational view of an electric mixer showing my new design.

Figure 2 is a top plan view thereof.

Figure 3 is a perspective view.

Figure 4 is a perspective view showing the side

of the electric mixer opposite to that which is shown in Figure 3.

I claim:

The ornamental design for an electric mixer, substantially as shown.
